BY
W. P. Hutchinson
ATTORNEY.

UNITED STATES PATENT OFFICE.

WILLIAM M. MIXER, OF NEW YORK, N. Y., ASSIGNOR TO WARREN B. HUTCHINSON, TRUSTEE, OF SAME PLACE.

STILL.

SPECIFICATION forming part of Letters Patent No. 591,138, dated October 5, 1897.

Application filed December 10, 1896. Serial No. 615,239. (No model.)

To all whom it may concern:

Be it known that I, WILLIAM M. MIXER, of New York, in the county and State of New York, have invented certain new and useful 5 Improvements in Stills, of which the following is a full, clear, and exact description.

My invention relates to improvements in stills; and the object of my invention is to produce a still which can be used for distilling various liquors, but which is especially adapted for use in connection with refrigerating-machines to distil out ammonia-gas from strong aqua-ammonia and leave the usual weak liquor.

15 The chief object of my invention is to construct a still of this kind in a practical and inexpensive way and in such a manner that it can be easily heated, and particularly to arrange a series of deflectors or baffle-plates 20 in such a way that the inflowing liquor will be forced to travel a circuitous route downward through the still and be finally subdivided, so as to expose the film or particles to the action of the heat, thereby causing the 25 still to work rapidly and efficiently.

Another object of my invention is to provide an easy and inexpensive means of supporting the aforesaid baffle-plates or deflectors and combine in this support a siphon-pipe 30 through which the weak liquor in the still may be withdrawn.

To these ends my invention consists of certain features of construction and combinations of parts which will be hereinafter described and claimed.

35 Reference is to be had to the accompanying drawings, forming a part of this specification, in which similar figures of reference indicate corresponding parts in all the views.

40 Figure 1 is a central vertical section of my improved still. Fig. 2 is a broken detail sectional view of one of the internal steam heating-pipes in the still. Fig. 3 is a plan view of the spider which steadies the heating-pipes. Fig. 4 is a plan view of one of the 45 larger deflectors or baffle-plates, and Fig. 5 is a similar view of one of the smaller deflectors or baffle-plates.

The still has the usual elongated shell 10, 50 which is of the ordinary construction, and

has the top closure 11 and bottom closure 12, which closures are also common. Beneath the still and formed in a subbottom is the steam-chamber 13, which has the steam-inlet 14 and the water-outlet 15^a, the latter extending from a chamber or space 15 between the top of the chamber 13 and the bottom 12. No novelty is claimed for this arrangement. The still is supported on a suitable bracket or brace 16.

55 The heating apparatus occupies the lower part of the still and comprises a series of vertical pipes 17, which are relatively large in cross-section and which extend upward from the bottom 12, these pipes each containing an 60 internal steam-pipe 18, which extends upward nearly to the top of the pipe 17 and connects with the steam-chamber 13. Sufficient space is left around each pipe 18 to permit the condensed steam to drain off into the 65 space 15 and so out through the vent 15^a. The circulation and heating of the pipes is better if the outlet at the top of each pipe 18 is reduced, as shown at 19 in Fig. 2. This 70 reduction in the top of the pipes 18 causes an 75 even distribution of heat. If the pipes are not reduced at the top, the steam entering the chamber 13 passes quickly up through the pipes 18 on the side nearest the inlet 14, while the pipes on the farther side of the still 80 are comparatively cool, but when the vents 85 are reduced the steam cannot escape fast enough through the first-mentioned pipes, and so it passes up through all the pipes, and hence the still is evenly heated. The tops of 90 the pipes 17 are stayed by the spider 20, which is fastened transversely in the shell 10 and has a series of sockets 21 to receive the connections or plugs at the top of the pipes 17. The arrangement of the heating-pipes is not 95 expressed.

The strong aqua-ammonia or other matter to be distilled is admitted at the top through a pipe 22, which delivers on the upper of a 95 series of deflectors 23 and 27, which are regularly spaced and placed alternately in the still, as will be more specifically described presently. Each deflector 23 is of a diameter to just fit closely in the shell 10, and it has 100

a central opening 24, through which the liquor passes in its downward course and through which the vapor rises, this opening being surrounded by a rim 25, which is lower than the outer rim of the deflector and which is serrated, as shown, so that the liquor, instead of passing over at some one point in a stream, is subdivided into numerous parts and trickles down through each serration in a small body, so as to be subjected to the influence of the heat arising in the still. Each deflector 23 is also provided with a central spider 26, which connects with the supporting-pipe 29 of the still and so braces the deflector. This arrangement makes a cheap construction, and the deflectors are braced by the pipe 29, while the latter is also braced by the deflectors.

The liquor which passes over the rim 25 of a deflector 23 falls into a deflector 27, which is arranged a little below the deflector 23 and which is closed at the bottom, except for the opening 28, which fits snugly on the supporting-pipe 29. The deflector 27 is of less diameter than the deflector 23, but of greater diameter than the opening 24 in the deflector 23, and the deflector 27 has an outer serrated rim 27^a, through which the liquor passes in a subdivided condition and falls on the next deflector 23 below. The pipe 29, which serves as a support for the deflectors, also serves as an exhaust-pipe through which the weak liquor in the still may be siphoned out, and it connects with a central top opening 30 of the still. The deflectors are spaced on the pipe 29 by means of sleeves 31, and nuts 32 are threaded on the pipe to maintain the sleeves. The vapor or gas distilled from the strong aqua-ammonia passes out through an opening 33 in the top of the still. It will be understood that any necessary number of deflectors 23 and 27 can be used, and by reference to Fig. 1 it will be seen that the alternate arrangement of the larger and smaller deflectors causes the liquor which enters the still to pass from the upper deflector 23 to the next deflector 27, from that to the second de-

flector 23, and so on, the liquor being all the time exposed to the rising heat.

In practice the liquor or aqua-ammonia is permitted to flow fast enough to keep the still full to a point above the heating-pipes 17, and the liquor or aqua-ammonia is thereby boiled in the still, so that the vapor or gas arising from the body of ammonia or liquor and from the descending ammonia or liquor causes the still to work very rapidly and effectively.

Having thus described my invention, I claim as new and desire to secure by Letters Patent—

1. The combination with the still, of the discharge-pipe extending centrally downward into the still, and alternating series of transverse deflectors discharging one upon the other, the smaller deflectors being secured to the discharge-pipe, and the larger deflectors being secured to the discharge-pipe and extending against the still-walls, the larger deflectors being provided with central openings, substantially as described.

2. The herein-described still, comprising a shell having an internal heating apparatus at the bottom, a discharge-pipe extending from the top downward into the still, a series of transverse deflectors held within the still, the smaller of said deflectors being secured to the discharge-pipe, and the larger being secured to the discharge-pipe and arranged to engage the still-walls, an inlet delivering upon the upper deflector, and a gas-outlet at the top of the still, substantially as described.

3. The combination with the still having deflecting apparatus therein as specified, of the heating apparatus, comprising a series of relatively large exterior pipes closed at the top, a series of internal pipes contained in the larger pipes, and provided with reduced vents, a steam-supply for the interior pipes, and an outlet for the exterior pipes, substantially as described.

WILLIAM M. MIXER.
